UNITED STATES PATENT OFFICE.

GUSTAV UNTERBERG, OF DURLACH, GERMANY.

IGNITION APPARATUS FOR STARTING INTERNAL-COMBUSTION ENGINES.

1,132,987.

Specification of Letters Patent. Patented Mar. 23, 1915.

Application filed March 26, 1912. Serial No. 686,272.

To all whom it may concern:

Be it known that I, GUSTAV UNTERBERG, engineer, a citizen of the German Empire, residing at Durlach, in the Grand Duchy of Baden; Germany, have invented certain new and useful Improvements in Ignition Apparatus for Starting Internal-Combustion Engines, of which the following is a specification.

- 10 Various auxiliary devices are already known for driving the armature of a magneto electric ignition apparatus while the engine is stationary under compression, so as to produce a spark in the gas mixture in the cylinder. These have comprised a tension cord or rod extending to the driver's seat and serving to tension an armature driving device which is then suddenly released so that the armature is driven at the 20 necessary speed in the magnetic field. These devices, however, have not become established on the market because on the one hand the rough handling to which the driving rod is unavoidably subjected in use leads to continual repairs, and on the other hand the provision of a carefully arranged remote drive extending to the driver's seat is a source of great advantage especially in vehicles. According to this invention such a 25 remote drive is obviated by the insertion of a spring device between the armature and the part which drives it, (the two being relatively movable), which is tensioned as the moving parts come to a standstill when the 30 engine is put out of action by the rotation of the member which drives the armature, the armature itself being held still by the action of a speed measuring device. The tension is maintained by a locking device 35 which comes into action after a determined amount of relative rotation, the speed measuring device which holds the armature stationary being put out of action at the same instant. A spark can then be produced, 40 when it is desired to start the engine, in the cylinder under compression, by release of this locking device.

The speed measuring device for holding the armature stationary advantageously consists of a ball subjected to centrifugal force, such as is employed in known driving devices comprising two clutch parts of which one connected to the driving shaft is held still at slow speeds of the engine by the engagement of the ball between it and a pro-

jection on a casing so that it may snap forward at the instant of sparking, while at high speeds the locking device is automatically released or put out of action in consequence of the outward movement of the ball.

In the construction according to the invention a control cord is only required to enable the locking device to be withdrawn by the driver and this does not need careful erection or arrangement such as is necessary in a device which has to transmit the power required to tension the driving spring, and in which, in particular, regard must be had to the necessity of allowing the device to return rapidly to its initial position when the armature snaps forward.

The accompanying drawings illustrate one form of construction according to the invention; Figure 1 showing the auxiliary drive together with the ordinary means for driving the ignition apparatus; Fig. 2 a front view of the ignition apparatus; Fig. 3 is a section on a reduced scale taken on the line 3—3, Fig. 1, and looking in the direction of the arrows; Fig. 4 is a section on a reduced scale taken on the line 3—3, Fig. 1, and looking in the opposite direction from Fig. 3; and Fig. 5 the controlling device at the driver's seat.

a is the end of the armature shaft. On this is keyed the clutch member *d* to which is attached one end of the spring *e* which serves to drive the armature. The other end of the spring is fastened in suitable fashion to the second clutch member *c* which is rotatably mounted on shaft *a* and carries the cone *b* through which the drive for the armature is transmitted. The two clutch members *d* and *c* are connected together not only by spring *e* but also by a projection engaging in a sufficiently long slot *i*, as shown in Figs. 3 and 4, so that the turning moment applied to cone *b* is transmitted directly to shaft *a* and the armature. The device dependent on the speed of the ignition apparatus for holding the armature stationary consists of the ball *h* guided in a radial slot *s* in the clutch member *d*; this is moved by centrifugal force outward to the end of the slot when the armature is rotating quickly, but when the speed falls gradually through the engine being put out of action, it returns to the inner end and so comes against the projection *f* on the casing, which the member *d* can rotate past because of the annular

slot *g*. By this means the armature is held stationary and the parts of the engine still in rotation now turn the clutch member *c* relatively to the clutch member *d* so tensioning the spring, until the pin *k* mounted in the member *c* snaps under the pressure of the spring *m* into the recess *l* in the member *d*. Obviously the slot *i* must be long enough for the parts *d* and *c* to turn to this extent 10 (as shown more clearly in Figs. 3 and 4).

A recess *r* is provided in member *c* which comes opposite the slot *s* in member *d* when the pin *k* enters the recess *l*, *i. e.* when the spring *e* is tensioned. Consequently as soon 15 as any pressure is exerted by the clutch members which are held together by pin *k*, the ball *h* will move into the recess *r* until the slot *S* and the recess *L* move away from each other, after which the pressure of the 20 two members *C* and *D* will again force the ball back into the slot *S*, but at such a time when the projection *F* on the casing will have passed beyond the point where it can catch the ball and lock the member *D* to the 25 casing and thus the armature will be left free to rotate.

In front of the part carrying the pin *k* is mounted a ring *n* which when moved backward against the action of the spring *m* uncouples the members *d* and *c*. Part *c* being held stationary by the stationary engine, spring *e* throws the armature forward. A control cord extends from ring *n* to the drum *t* of the ignition switch seen in Fig. 5, 35 the lever *o* of which is held in the proper position by the spring pin. The cord drum is formed also as a contact carrier. There is nothing special in the construction shown for the sake of completeness in Fig. 5.

40 The operation of the device is as follows:— When the motor is rotating the ball *h* lies at the upper end of the slot *s*, so that the clutch parts *d* and *c* transmit the drive from the engine to the ignition device through their 45 engagement by the pin and slot *i* and of the spring *e*. As soon as the engine is put out of action and its speed has diminished in consequence, the ball *h* moves inward as indicated in Figs. 1 and 3 and becomes clamped in the 50 slot *s* against the projection *f*, so that the clutch member *d* is held stationary while the armature moves on under the inertia of the moving masses until the pin *k* upon it springs into the recess *l* 55 in the member *d*. In this position the slot *s* of the clutch member *d* is opposite the recess *r* in the member *c* so that as the rotating masses press the two members farther the ball is forced into the recess *r* this moving 60 being facilitated by the sloping surface of the projection *f* on the casing. The parts *d* and *c* thus connected by the pin *k* now continue rotating together until the engine comes to a standstill. If now the engine is 65 to be started again all that is necessary is

to pull the controlling cord so as to withdraw the pin *k* from the recess *l*. By this means the clutch member *d* with the armature is thrown forward by spring *e* relatively to the member *c* which is held stationary with the stationary engine until the pin engaging in slot *i* reaches its end. By this means an igniting spark is produced in the cylinder under compression. 70

Having thus described my invention, what 75 I claim as new and desire to secure by Letters Patent of the United States is:

1. In an electromagnetic ignition apparatus, the combination of an armature and a driving member, a spring arranged between the armature and its driving member and connected therewith; and a device moving under centrifugal force adapted to lock the armature to the casing when said device is in innermost position but to leave it free at 80 high speeds; with a spring pressed pin on the driving member adapted to lock same to the armature after a certain relative rotation, said driving member having a slot to permit release of the locking device after 85 this rotation has occurred.

2. In a magneto electric ignition apparatus, the combination with a casing, of a driving member and a driven member having a radial slot, a device in said slot adapted to 95 lock said driven member to the casing when in its innermost position, means for placing the driving member under torque with relation to the driven member, and means carried by the driving member adapted to interlock 100 with the driven member and to be unlocked therefrom.

3. In a magneto electric ignition apparatus, the combination with a casing, of a driving member and a driven member having a radial slot, a ball in said slot adapted to lock said driven member to the casing when in its innermost position, a spring between said driven and driving members adapted to place them under torque with 110 relation to each other and means carried by the driving member adapted to interlock with the driven member and to be unlocked therefrom.

4. In a magneto electric ignition apparatus, the combination with a casing, of a driving member and a driven member having a radial slot, a device in said slot adapted to lock said driven member to the casing in its innermost position, a spring between said 120 driving and driven members adapted to place them under torque with relation to each other, and a spring-pressed pin carried by the driving member and adapted to interlock with said driven member and to 125 be unlocked therefrom.

5. In a magneto electric ignition apparatus, the combination with a casing, of a driven member having a circumferential slot, a driving member having a lug there- 130

on engaging said slot, a second radial slot in said driven member, a device in said slot adapted to interlock with a lug on said casing, a spring between said driven and driving members adapted to place said members under torque when said driven member is locked to said casing, and means carried by said driving member adapted to interlock with said driven member after a cer-

tain relative movement of said member and 10 adapted to be unlocked therefrom.

In testimony whereof I affix my signature in presence of two witnesses.

GUSTAV UNTERBERG.
